UNITED STATES PATENT OFFICE

ROBERT GOOD, OF WASHINGTON, PENNSYLVANIA, ASSIGNOR TO HAZEL-ATLAS GLASS CO., OF WHEELING, WEST VIRGINIA, A CORPORATION OF WEST VIRGINIA

GLASS FEEDING APPARATUS

Application filed March 24, 1926, Serial No. 97,051. Renewed April 25, 1931.

The invention relates generally to improvements in that type of feeder in which the glass is fed in shaped suspended mold charges, by means of an implement reciprocating in vertical alignment with the flow orifice of the flow spout. One of the objects of the invention is to generally improve the construction of this type of feeder, whereby the same may be more easily adjusted, and will at all times be under the control of the operator in a most convenient manner.

Another object of the invention is to provide an operating mechanism which will effect a great saving of compressed air or other operating fluid, in that the amount of operating fluid required will be substantially reduced as the length of stroke is reduced.

Further objects and advantages of the invention will be apparent to those skilled in the art, from the following detailed description taken in connection with the accompanying drawings; in which:

Figure 1 is a side elevation of the complete apparatus; the usual flow spout being shown in dotted outline.

Figure 2 is a plan view of the apparatus.

Figure 3 is a detail vertical sectional view taken on line 3—3 of Figure 1.

Figure 3a is a detail horizontal sectional view taken on line 3a—3a of Figure 1.

Figure 4 is a vertical sectional view of the feed plunger operating cylinder, and showing the adjusting means associated therewith.

Figure 5 is a vertical sectional view of the vertically adjustable bracket, and associated parts; and

Figure 6 is a bottom plan view of said bracket.

Referring to the drawings more in detail, numeral 1 indicates in dotted outline a conventional flow spout provided with the usual flow orifice 2. Arranged below the flow orifice are the usual shears (not shown) for severing the shaped suspended gobs to be fed to a forming machine.

Mounted for reciprocation in the flow spout, in vertical alignment with the flow orifice, is the ordinary feeder plug 3. This reciprocable plug is attached to an operating

rod 4 in any desired manner, but the particu-

lar means I have employed in practice and illustrated herein, consists of the following: An angular member 5 is removably attached to the lower end of the rod 4 and partly surrounds the feeder plug 3, and a pin 6 is secured in the member 5 and enters a hole 7 in the plug. For holding the plug rigidly in place I provide a clip 8 loosely mounted on the screw 9. This clip is moved into operative position by setting up on the nut 10. It is apparent by an inspection of the drawings, that when the clip is in operative position one end thereof will press against the operating rod 4, and the other end will press against the feeder plug 3, thereby holding the reciprocating parts in vertical alignment with the flow orifice.

The operating rod 4 is slidably mounted in bearings 11, 11, on a bracket 12. A crosshead 13 is adjustably secured adjacent the upper end of operating rod 4 by means of a set screw 14; and pivotally attached to the crosshead are links 15, 15, which links are pivotally attached at their lower ends to the walking-beams 16, 16. These walking-beams are pivotally mounted at 17 on a slide bracket 18, to which the bracket 12 is rigidly attached; and the ends of the walking-beams remote from the feeder are pivotally attached by means of a pin 19 to a link 20; the latter being pivotally attached at its lower end to a fork 22 by means of a pin 21.

Numerical 23 indicates the piston rod of the cylinder 24 which reciprocates the feeder implement. For reasons to appear herein-after it is essential that this piston rod be rotatable with respect to the fork 22, and the specific structure by which this is accomplished is illustrated in Figure 4, to which reference is now to be had. The upper end of the piston rod is provided with a tapped hole, into which the screw 27 is screwed and secured. Loosely mounted on the screw 27 is a collar 25 which is screw-threaded on its outer side and which is flanged at its lower end, as indicated by numeral 26. This collar is held in place on the piston rod by means of the above-mentioned screw 27, but it is understood that the collar 25 is free for turning movement with respect to the piston rod.

23. And as clearly shown in Figure 4, the fork is screw-threadedly secured to the collar 25, so that the collar and fork form in effect a single unit with respect to which unit the piston rod 23 may be freely rotated.

5. Figure 4 also illustrates the particular mechanism by which the limits of stroke of the piston rod may be simultaneously adjusted, and by which mechanism very considerable saving of compressed air or other operating fluid, is effected. However, this mechanism may best be described hereinafter; and therefore before describing this mechanism I shall describe the structure by which the feeder plug may be adjusted in various directions with respect to the flow orifice.

In addition to the means for adjusting the limits of the feeder stroke, to be described hereinafter, this device includes mechanism 20 for effecting three separate and distinct adjustments of the feeder plug with respect to the flow orifice, as follows:

First, means for bodily raising or lowering the feeder plug with respect to the flow orifice; that is, means for simultaneously raising or lowering both limits of the feeder stroke without changing the length of the stroke.

Second, means for moving the plug laterally with respect to the flow orifice.

Third, means for circumferentially adjusting the plug about the main supporting shaft as an axis.

These various adjusting means will now be 35 described in the order named.

In the specific structure illustrated herein, a bracket 28 is attached to the flow spout casing, and this bracket is provided with bearings 29, 30, in which a shaft 31 is rotatably mounted. To permit rotation of the shaft 31, and at the same time prevent vertical translation thereof, collars 32 and 33 are attached to the shaft, respectively above and below the bearing 30, and arranged between the upper collar 32 and the bearing 30, is a ball-bearing race 34.

Attached to the lower end of the shaft 31 is a bevel gear 35, which may be operated by a handle 36. However, it is sometimes desirable 50 to make the adjustment from a remote point, and accordingly I employ a bevel pinion 37 meshing with the bevel gear 35, and mounted on a shaft 38 which extends to any point convenient for operation.

55. Referring now particularly to Figures 5 and 6, it will be seen that the shaft 31 extends upwardly through a sleeve 39; the upper end of the shaft being reduced in diameter and screw-threaded. A nut 40 is screwed down on the reduced portion of the shaft 31, into position in the sleeve 39, and is locked in place in the sleeve by means of a screw 41. It is thus apparent that the sleeve 39 is supported by or suspended from the upper end 60 of the shaft 31, and that by rotation of the

shaft the sleeve will be raised or lowered, depending upon the direction of rotation.

The lower end of the sleeve 39 is cast integral with, or attached to, a supporting plate 42; the specific structure of the plate being 70 shown by the bottom plan view thereof, in Figure 6.

The slide bracket 18, carrying the feeder plug and associated operating parts, including cylinder 24, is mounted on the supporting 75 plate 42.

It is thus apparent that by the rotation of the shaft 31, the feeder plug and its entire operating mechanism may be raised or lowered to the desired extent, thereby varying 80 the vertical position of the plug with respect to the flow orifice, at both the upper and lower limits of the plug stroke, but in no way varying the length of the plug stroke.

The means for adjusting the plug laterally 85 with respect to the flow orifice, will now be described.

The supporting plate 42 is, of course, fixed against lateral sliding movement, as the sleeve 39 which is integral with the supporting plate, embraces the shaft 31. However, the bracket 18, which carries the feeder plug, its operating parts, and its operating cylinder, is laterally slidable on the plate 42. The bracket is secured to the supporting plate by 90 means of bolts 43 which pass through openings 44 in the supporting plate; and to permit lateral sliding adjustment of the bracket these openings 44 are elongated, as clearly 95 shown in Figure 6. Also to provide clearance for the cylinder 24, which is bolted to the sliding bracket 18, the supporting plate is provided with an elongated opening 45.

Depending from the supporting plate 42 is a lug 46, and threaded therein is a screw 105 47. The screw has a reduced portion 48 which is located in an aperture in plate 49 rigidly attached to the cylinder 24. The hand wheel 50 is mounted on the outer end of the screw, and the hub 52 of the hand wheel abuts against the outer face of the plate 42, thereby holding the screw against longitudinal movement with respect to the plate.

From the above description it will be apparent 110 that when the adjusting member 50 is rotated the plate 49 will be moved to the right or left (Fig. 1). The plate 49 is attached to the cylinder 24, the cylinder is attached to the bracket 18, and the bracket 18 115 carries the reciprocable feeder plug and its associated operating parts, so that when the plate 49 is moved, the feeder plug, the bracket, the operating cylinder and all connecting elements will be moved bodily to the same 120 extent, thereby laterally adjusting the feeder plug with respect to the flow orifice. The means by which the feeder plug may be circumferentially adjusted about the supporting shaft 31, will now be described. 125

5 A plate 53 is pivotally mounted on the shaft 31 and is supported on the upper surface of the bearing or bracket 29. An extension 54 is attached to the bracket 29, and a screw 55 is mounted in this extension against longitudinal movement, as clearly shown in Figures 3 and 3a; the screw being operated by the hand wheel 56.

10 A lug 57 is integral with or attached to the underside of the plate 53, and is tapped to receive the adjusting screw 55. Lug 57 has a depending stud 57^a, passing through a slot 54^a in extension 54, and furnished with a nut and washer 57^b. Normally the nut 57^b is tightened and holds the apparatus rigidly in adjusted position. It is thus apparent that when the hand wheel 56 is rotated, after the nut 57^b has been loosened, the plate 53 will be swung back or forth about the shaft 31 20 as a pivot. Slots 55' in the extension 54 allow for limited side movement of the screw 55 when the latter is rotated.

25 The plate 53 is provided with a wide slot 58 to receive the lower stuffing box of the cylinder 24, and the walls of this slot closely fit the depending plate 49 carried by the cylinder. So that, as the plate 53 is moved about its pivot (shaft 31), it will carry with it the cylinder 24, bracket 18 and feeder plug 3, thereby adjusting the plug either toward the front or rear of the flow spout, as may be necessary to properly align the plug with the flow orifice.

30 Thus if the feeder plug has become deformed, or in any manner has been thrown out of alignment with the flow orifice, it may, by the rotation of the hand wheel 50 or the hand wheel 56, be moved laterally to bring it into true alignment with the orifice. Or if glass being of different temperatures on different sides of the orifice causes the gobs to incline to one side as they leave orifice, they can be made to assume a vertical position by changing the relation of the point 45 of the plug to the orifice, by the various adjusting means described above.

40 The particular means employed for simultaneously adjusting the upper and lower limits of the feeder plug stroke, and by which means a considerable saving of compressed air or other operating fluid is effected, will now be described.

45 Referring particularly to Figure 4, it will be noted that the piston rod 23, within the cylinder 24, is provided with right and left handed threads and that mounted thereon are two pistons 59 and 60. Ports 61 and 62 deliver the operating air above and below the piston heads 59 and 60 respectively. To provide against the turning of the pistons a rod 63 is passed through holes therein, and the rod is floatably secured in place by inserting the ends thereof in recesses provided in the cylinder heads 64 and 65.

50 Mounted on the lower end of the piston rod

is a notched wheel 66, by means of which the piston rod may be rotated to adjust the pistons. It is apparent, of course, that after the pistons have been adjusted, the piston rod must be held against further rotation until another adjustment is desirable. For this purpose I provide a vertical bar 67 which is carried by rods 68, positioned in key hole slots 69 in the plate 49, the slots being shown generally by dotted lines in Figure 1. With these parts in the position shown in Figure 1, it is apparent that the rod engages one of the notches in wheel 66, thereby preventing rotation thereof, yet at the same time permitting the piston rod to be reciprocated. Now if it is desired to rotate the notched hand wheel to adjust the pistons, it is only necessary to lift the rods 68 by the handle 70, until the round rods are brought into alignment with the round part of the key hole slots, and then retract the members sufficiently to disengage the vertical bar 67 from a notch in the hand wheel 66, whereupon the wheel may be turned to move the pistons to the desired position. After proper adjustment the bar 67 will be moved into engagement with one of the notches, and the locking mechanism will be lowered by the handle 70 to bring the flattened portions of the rods 68 into the narrow portions of the key hole slots, thereby securing the locking means against accidental displacement.

55 Counterweights 71 are employed to equalize the pressure required to raise and lower the piston rod.

60 The operation of the adjusting means within the cylinder 24 will be understood from the foregoing description. If the piston rod 23 is turned in one direction the pistons 59 and 60 will be simultaneously moved toward each other, thereby simultaneously raising the upper limit of the feeder plug stroke and lowering the lower limit of the stroke; while if the piston rod is turned in the opposite direction the pistons will be simultaneously moved away from each other, thereby simultaneously lowering the upper limit of stroke and raising the lower limit of stroke.

65 Further, the adjusting means described above effects a very material saving of operating fluid. It will be apparent from an inspection of Figure 4 that the operating fluid is supplied only to those portions of the cylinder above the piston 59 and below the piston 60; the portion of the cylinder between the piston being a dead air space. When the pistons are moved toward each other the effective length of the cylinder is increased, and when they are moved away from each other the effective length of the cylinder is decreased. The amount of compressed air employed varies in accordance with the length of stroke, so that as the length of stroke is reduced the amount of compressed air or

other operating fluid required, is also reduced.

The operations of the several adjustments have been described hereinbefore, and there is no necessity for further description of the operation. By rotation of the hand wheel 50 the feeder plug is moved toward the right or lift (Figure 1) to bring it into true alignment with the flow orifice. By rotation of the hand wheel 56 the feeder plug is moved toward the front or rear (Figure 1) to bring it into true alignment with the flow orifice. By rotation of the shaft 31 the limits of the feeder plug stroke are simultaneously varied in the same direction, either upwardly or downwardly, whereby the length of stroke remains the same but the vertical position of the path of stroke with respect to the flow orifice, is changed. By rotation of the piston rod 23 the limits of the feeder plug stroke are simultaneously varied in opposite directions, thereby varying the length of the stroke as well as varying the limits thereof.

Obviously, the invention disclosed herein is subject to numerous changes and modifications, and it is my intention to include all such changes and modifications within the scope of the appended claims.

Having fully described the invention, what I claim as new and desire to secure by Letters Patent is:

1. A glass feeder including a movable feeder implement, a cylinder and piston rod operatively connected with the feeder implement, and means mounted on the piston rod for simultaneously adjusting the limits of stroke of the feeder implement, said means being adjusted by movement of the piston rod.

2. A glass feeder including a reciprocable feeder implement, a cylinder and piston rod operatively connected with the feeder implement, and means mounted on the piston rod for simultaneously adjusting the limits of stroke of the feeder implement, said means being adjusted by rotation of the piston rod.

3. A glass feeder including a reciprocable feeder plug, a cylinder and piston rod operatively connected with the feeder plug, and means arranged within the cylinder for simultaneously adjusting the limits of stroke of the piston rod.

4. A glass feeder including a movable feed control implement, a cylinder and piston rod operatively connected with said implement, said piston rod having a threaded portion within the cylinder, and two pistons threaded thereon, said pistons being simultaneously adjusted longitudinally of the piston rod by rotation of the latter.

5. A glass feeder including a movable feeder implement, a cylinder and piston rod operatively connected with said implement, said piston rod having oppositely threaded portions within the cylinder, and a piston thread-

ed onto each of the said portions, whereby said pistons are simultaneously adjusted toward or from each other by rotation of the piston rod.

6. Means for feeding glass including, a flow spout provided with a flow orifice, a feeder plug adapted to reciprocate in the flow spout in vertical alignment with the flow orifice, a cylinder and piston rod operatively connected with the feeder plug, said cylinder provided with a port adjacent each end thereof, and two pistons oppositely threaded on said piston rod within the cylinder.

7. Means for feeding glass including, a flow spout provided with a flow orifice, a feeder plug adapted to reciprocate in the flow spout in vertical alignment with the flow orifice, a cylinder and piston rod operatively connected with the feeder plug, two pistons oppositely threaded on said piston rod within the cylinder, and means for holding the pistons against rotation.

8. A glass feeder including a movable feeder implement, a cylinder and piston rod operatively connected with the feeder implement, said piston rod being rotatable, two pistons oppositely threaded on the piston rod within the cylinder, means for rotating the piston rod, and means for securing the piston rod against rotation.

9. A glass feeder including a movable feeder implement, a cylinder and piston rod operatively connected with the feeder implement, two pistons mounted on the piston rod for limiting the piston stroke, and means outside of the cylinder for adjusting one of said pistons.

10. A glass feeder including a movable feeder implement, a cylinder and piston rod operatively connected with the feeder implement, two pistons mounted on the piston rod for limiting the piston stroke, means outside of the cylinder for adjusting one of said pistons, and means for maintaining such piston in adjusted position.

ROBERT GOOD.
